UNITED STATES PATENT OFFICE

SAMUEL S. STOLP, OF LOUISVILLE, KENTUCKY, ASSIGNOR TO CHEATHAM ELECTRIC SWITCHING DEVICE CO.

ELECTRIC SWITCH CONTROL

Application filed July 23, 1927. Serial No. 207,924.

My invention relates to electrically operated track switches operated electrically from the car.

One object of my invention is to produce a system that works "power on" or "power off" the system as hereinafter described.

This invention relates to improvements in electrically operated switch controls in which solenoids, contactors and circuits are grouped 10 to produce the following objects:—

First, to increase the life of the apparatus; second, to increase the speed of operation; third, to introduce a time element in the switch operating circuit that will open the 15 circuit within the operating length of the contactor; and fourth, to introduce a time element in the switch operating circuit that will limit the time of current application to the track solenoids, this being the maximum pre- 20 determined time.

These objects are attained by the apparatus illustrated in the accompanying drawings in which—

Fig. 1 is a section of the control panel 25 showing the general arrangement of the relays employed in the system.

Fig. 2 is a general arrangement of the circuits and parts when the system is in a normal condition.

Throughout the various figures and drawings it was attempted to retain the same numerals for similar parts, so the description of the various modifications would be more readily understood.

In Fig. 1 the numeral 2 represents a retarded pickup time element that is employed to open the switch operating circuit for a predetermined time interval. The letter X represents the current selective relay employed 35 to produce the track switch solenoid selection, and its operating functions are the same as formerly used in the art. In the retarded pickup relay 2, 1 is the magnet core for the coil 3 and copper slug 4, and is secured to the 40 magnet frame that carries the armature 5^a. The contact arm 6 which carries the contact 45 6^a, normally rests against the fixed contact 7 and has a separate bearing point 6^b. It can be readily seen by reference to the drawing 50 that the armature 5^a, during its course of

travel, will strike the contact arm 6 and cause it to move away from the contact 7 with a very quick movement. It will also be noted by reference to the dotted lines for relay 2 that after the completion of this hammer 55 blow effect the contact arm will return to rest in a mid position, being stopped on its return course of travel by the armature 5^a. It is the purpose of this arrangement to permit the contact arm to return a portion of its travel, 60 and come to rest before the contacts 6^a and 7 close, so as to avoid any excessive or deteriorating wear on the contacts. The relay X has a similar core and magnet frame to relay 2, and is equipped with an operating 65 coil KL, an armature KL^a that carries a contact which operates between the back contact 19 of relay X and front contact 18 of relay X.

In Fig. 2, relays 2 and X are represented 70 by the conventional symbols. In this system numeral 9 represents a trolley wire or conductor. Positioned adjacent the trolley conductor is a pan or trolley contactor 8 provided with two contact members 10 and 11 which 75 are generally parallel and normally insulated from each other. The member 10 is electrically connected to the trolley conductor 9 at all times, but the member 11 is normally insulated therefrom, but it is electrically connected thereto when a current collector engages the pan or trolley contactor 8. The contact members 10 and 11 are so related to the trolley conductor 9 that when the current 80 collector engages the contact members it will 85 be out of engagement with the contact members and remain so until it is about to pass out of engagement with the pan or trolley contactor. Such arrangement of the contact members and conductor is well known to 90 those skilled in the art. I also employ an electrically operated track switch that is provided with two solenoids GM^a and GM^b each having a connection to the ground through the common conductor 24.

I also employ an electrically operated normally open relay X provided with an operating coil KL and an armature KL^a. The coil KL is mounted on a magnet core which is also true of the other switch coil later referred to, 100

although a moving plunger may be substituted for the magnet core as is well known to those skilled in the art. One terminal of coil KL is connected to the contact member 10 of trolley contactor 8 by wire 13, and the other coil terminal is connected to the trolley conductor 9 by wire 12. The armature KL^a of relay X is normally in its free state; that is, not influenced by any magnetic flux and rests against the normally closed contact 19 which is a back contact of relay X and is connected through wire 1^b to the contact arm 6 of the retarded pickup relay 2. The back contact 19 of relay X is connected by wires 2^b and b to track switch operating solenoid GM^b. The front contact 18 of relay X is connected by wires 2^a and A to track switch operating solenoid GM^a.

The other relay T that I employ has in addition to its operating coil 3, a copper slug 4 and an armature 5^a. The armature 5^a has no electrical connection in the circuit and is used to mechanically move the contact arm 6 which in turn controls the contacts 6^a and 7. One coil terminal of coil 3 is connected by wires 16 and 17 to the divided resistor 17^a, 17^b, the other coil terminal of coil 3 of relay 2 is connected to the back contact 7 of relay 2 by wires 15 and 7^a.

30 The relay 2 is provided with a retarded pick up factor and this retardation may be brought about by many well known constructive principles, such as a copper or brass slug about the core of the coil of the relay, as indicated by 4, or it may be brought about by the spacing of the armature 5^a with respect to the core when in the open position or a combination of these, or a dash-pot et cetera, may be employed. It is also very evident to those skilled in the art that the armature 5^a can be calculated to operate with a relatively slow magnetic response by reason of very high inductance of the operating coil 3, and this means is employed very extensively in the 40 system disclosed in Fig. 2, which I describe 45 more fully in a later description.

It must be remembered that the switch operating relays GM^a and GM^b are wound with a relatively low resistance whereby a high wattage results to produce a normal saturating value capable of causing actuation in either of the coils when they are in the operating condition. Therefore, it is very desirable to have a reliable and safe time element 55 to remove the current from these coils after they have been given enough time to perform their operations. It must also be remembered that the operating coil KL of relay X has a very low resistance; that is, it generally 60 consists of six or eight turns of #6 copper wire. Relay X is a current selective relay; that is, a very heavy current must pass through its operating coil KL before it can effect its armature KL^a. This current is always greater than any current used in the op-

eration of the control relays and track switch solenoids employed in the system. This current is always equivalent to one or two points power, i. e. one or two stages, stops or notches on the car motor controller, as may be used 70 by the car operator which is always greater than the auxiliary currents used by trolley cars.

In the system shown in Fig. 2, when the current collector or trolley wheel engages the trolley contactor 8 with "power off" operating coil KL of relay X is not energized to the point wherein it would affect its armature KL^a as the current passing through this coil at this interval would only be the auxiliary 80 currents of the car and the small currents that are employed to operate the relays and the solenoids of the system. As the current collector comes into contact engagement and bridges contact members 10 and 11, a circuit 85 is completed to the track switch operating coil GM^b, feeding from the trolley conductor 9, through wire 12, coil KL of relay X, wire 13, contact member 10, through the current collector, through contact strip 11, wire 14^a, fuse 14, wire 7^a, back contact 7 of relay 2, contact arm contact 6^a of relay 2, wire 1^b, armature KL^a of relay X, back contact 19 of relay X, wire 2^b, wire b, track switch operating solenoid GM^b, wire 23, wire 24 to ground G, and 95 the track switch operating mechanism will be operated to the "straight ahead" course, or held in this position depending upon the previous condition of the track switch. Instant to the establishment of this circuit the 100 retarded pickup relay 2 was brought into action by the completion of the circuit through its operating coil 3, the circuit being completed from the trolley conductor 9, wire 12, coil KL of relay X, wire 13, contact member 10 of trolley contactor 8, through the current collector, contact member 11 of trolley contactor 8, wire 14^a, fuse 14, wire 15, operating coil 3 of relay 2, wire 16, wire 17, resistance unit 17^a, wire 20, wire a, track switch 105 operating solenoid GM^a, wire 22, wire 24 to ground G. At this point it would be well to note that the current of this circuit is very small, always say, less than one-half of one ampere and this is not of sufficient magnitude to affect any operation of the track switch mechanism. After the predetermined time interval of the relay 2, the means heretofore described, the armature 5^a of relay 2 is effected, and is raised to closed position, wherein during its course of travel it strikes the contact arm 6, and opens contacts 6^a and 7 of relay 2. The opening of these contacts opens the track switch solenoid operating circuit that was completed through them. The 110 opening of these contacts, however, did not effect the circuit completed through the operating coil 3 of relay 2, as this circuit remains established as long as the current collector 115 engages the contact members 10 and 11 of 120 125 130

5 trolley contactor 8, to retain the contacts 6^a and 7 opened as heretofore described. As soon as the current collector W disengages the trolley contactor 8, the operating coil 3 of relay 2, is deenergized thereby permitting the contact arm 6 to be restored to its normal position. The circuit for the operating coil 3 of relay 2 was described as having a ground return path through only one-half of the 10 divided resistor 17^a-17^b, but it must be noted, however, that as soon as the contacts 6^a and 7 of relay 2 disengage, the circuit is then completed through the other portion of the divided resistor, as this portion of the return 15 circuit was inoperative through a shunt that was established through contacts 6^a and 7. The object of such an arrangement as this is to provide an accelerating circuit for the contact arm 6. It is evident that as the divided resistor provides two ground returns, the current through the operating coil 3 of 20 relay 2 is increased, thereby increasing the power of the relay at the time the work becomes the greatest. A secondary advantage 25 of such an arrangement is, as the retarding affect of the relay is being encountered the operating current for the relay is at a minimum thereby increasing the time factor of 30 operation.

35 If the current collector engages the trolley contactor 8 initially using "power on" the coil KL of relay X will be energized, as a current of sufficient magnitude is passing through it to produce an operation of its armature KL^a to the raised position, bringing it into contact engagement with the normally open front contact 18 of relay X. Instant to 40 the completion of this operation, and the engagement of the current collector and contact members 10 and 11 of trolley contactor 8, a circuit was completed to the track switch solenoid GM^a to affect an operation of the track switch operating device to the "curved" 45 position, the circuit being completed from the trolley contactor 9, through wire 12, coil KL of relay X, wire 13, contact member 10 of trolley contactor 8, through the current collector, contact member 11 of trolley contactor 8, wire 14^a, fuse 14, wire 7^a, back contact 7 of relay 2, contact arm contact 6^a of 50 relay 2, contact arm 6 of relay 2, wire 1^b, armature KL^a of relay X, front contact 18 of relay X, wire 2^a, wire A, track switch operating solenoid GM^a, wire 22, wire 24 to ground G. After a predetermined time interval the 55 relay 2 will operate in the same manner as was described for the "straight ahead" operation with the exception that its initial ground return was taken through the 17^b portion of the divided resistor 17^a-17^b, and track switch operating solenoid GM^a.

60 To sum up the operation of this system, if the car operator desires to go "straight ahead", he sets his controller to "power off" 65 with the intention of coasting past the trol-

ley contactor 8. As soon as the current collector engages the trolley contactor 8, the track switch will operate to the "straight ahead" position, and should he remain on the contactor the circuit for track switch operating solenoid will be opened, thereby affording the maximum protection available for the track switch operating solenoids. 70

If the car operator desires to take the "curve", he will turn his controller to "power on" with the intention of passing the contactor drawing power. When the current collector engages the trolley contactor 8 with power on, relay X will operate and select the "curved position" track switch operating 75 solenoid, and the track switch will be thrown to the "curved position." However, should the operator be compelled to bring his car to stop under the trolley contactor, the circuit of the track switch operating solenoid will be 80 opened and the same protection will be provided for the solenoids as described for the straight ahead position.

85 There are, of course, modifications and arrangements of the parts which may be made 90 from that shown in the above disclosure and which will still fall within the scope of my invention.

I claim:

1. In a system of the class described, the 95 combination of an actuating solenoid, a relay operable to selectively direct currents thru different parts of the actuating solenoid, and a second relay for controlling current flow to said solenoid and arranged to automatically 100 pickup upon a flow of current thru one of the actuating solenoids.

2. In a system of the class described, the 105 combination of an actuating solenoid, a relay operable to selectively direct current thru different parts of the actuating solenoid, and a second relay for controlling current flow to said solenoid and arranged to automatically 110 pickup upon a flow of current less than a normal saturating value for said solenoid thru one of the said actuating solenoids.

3. In a system of the class described, the 115 combination of an actuating solenoid, a relay operable to selectively direct currents thru different parts of the actuating solenoid, and a second relay for controlling current flow to said solenoid circuit and arranged to automatically 120 pickup upon a flow of current thru one of the actuating solenoids, and retain this state by a holding current flowing thru both branches of the actuating solenoid.

4. In a system of the class described, the 125 combination of a normally open operating circuit including an actuating solenoid, a relay adapted to selectively direct current in said circuit thru different parts of said solenoid, and a second relay in a circuit between the first mentioned relay and the solenoid for controlling a flow of saturating current thru either branch of the solenoid, 130

and arranged to automatically pickup upon a flow of current in said circuit less than a saturating value feeding thru the branch of the solenoid not selected.

5. In a system of the class described, the combination of a normally open operating circuit including an actuating solenoid, a relay adapted to selectively direct current in said circuit thru different parts of said solenoid, and a second relay in a circuit between the first mentioned relay and the solenoid for controlling a flow of saturating current thru either branch of the solenoid, and arranged to automatically pickup upon a flow of current in said circuit less than a saturating value feeding thru the branch of the solenoid not selected, and retain this state by a current feeding thru both branches of the actuating solenoid as long as the said normally open circuit remains closed.

10 6. In a system of the class described, the combination of a normally open operating circuit including an actuating solenoid, a relay adapted to selectively direct current thru different parts of said solenoid, a circuit including a second relay and a divided resistor connecting each branch of the solenoid of sufficient ohmic resistance to limit the current to less than necessary to saturate the solenoid, the armature of said relay being connected to shunt one portion of the divided resistor when a saturating current is being applied to a branch of the actuating solenoid to decrease the current flowing thru the operating means of the last mentioned relay until the said relay has functioned to open said branch circuit of the actuating solenoid.

15 7. In a system of the class described, the combination of a normally open operating circuit including an actuating solenoid, a relay adapted to selectively direct current thru different parts of said solenoid, a circuit including a second relay and a divided resistor connecting each branch of the solenoid of sufficient ohmic resistance to limit the current to less than necessary to saturate the solenoid, the armature of said relay being connected to shunt one portion of the divided resistor when a saturating current is being applied to a branch of the actuating solenoid to decrease the current flowing thru the operating means of the last mentioned relay until the said relay has functioned to open said branch circuit of the actuating solenoid, 20 wherein the current is increased thru the said operating means to insure a positive opening of the said branch circuit.

25 8. In a system of the class described, the combination of a normally open operating circuit including an actuating solenoid, a relay adapted to selectively direct currents thru different parts of said solenoid, a circuit including a second relay having an armature included in the said operating circuit and its operating means included in a circuit con-

necting the different parts of the solenoid, thru a high resistance, means to close the said normally open operating circuit and establish a saturating current thru one branch of the actuating solenoid and establish a current of less than a saturating value thru the other branch of the solenoid to effect the operating means of the last mentioned relay.

70 9. In a system of the class described, the combination of a track switch solenoid, a relay for selectively directing current thru different parts of the track solenoid, a second relay for controlling the flow of current to the track switch solenoid, a power line, a circuit including a trolley contactor having an element connected with the power line and an element connected thru the second relay, a divided resistor and the branches of the track solenoid to ground, and a second connection thru an armature of said second relay to a branch of the solenoid selected by said first relay.

75 10. In a switch operating system, the combination with a track switch point of a double solenoid operating means to operate it in one direction or the other and having one side of each solenoid connected to the ground, a trolley wire, a trolley contactor with a pair of parallel contacts arranged to be bridged by a current collector, a solenoid operating circuit leading from one contact to the solenoids to carry current to operate the solenoids when the current collector engages the trolley contactor, a selector switch interposed in said circuit for directing the current to one solenoid or the other at will, a time limit switch connected in said circuit to open said circuit and cut off said current after a predetermined time of flow, a circuit connecting the other contact of the trolley contactor with the trolley and having means therein to control the selector switch, a circuit connecting the time limit switch and one contact of the trolley contactor and including the track solenoids, and electrically operated means in said circuit to permit an operation of the time limit switch when a current collector bridges the contacts of the trolley contactor, electrically controlled means to permit a positive large initial opening of the time limit switch and permit it to be restored to a position other than a closed position as long as the current collector bridges the contacts.

80 11. In a system of the class described, the combination of an actuating solenoid, a relay operable to selectively direct currents thru different parts of the actuating solenoid, a second relay for controlling current flow to said solenoid, a divided resistor, divisions of said resistor connecting the second relay and the actuating solenoid, said resistor so connected as to provide a shunt path for the initial operating current for the last mentioned relay.

85 12. In a system of the class described, the

combination of an actuating solenoid, a relay 5
operable to selectively direct currents thru
different parts of the actuating solenoid, a sec-
ond relay for controlling current flow to said
solenoid, a divided resistor, divisions of said
resistor connecting the second relay and the
actuating solenoid, said resistor so connected
as to provide a shunt path for the initial op-
erating current for the last mentioned relay,
and provide a second ground return for the
said relay after a predetermined time to in-
crease its operating current.

13. In a system of the class described, the
combination of an actuating solenoid, a re-
lay operable to selectively direct currents thru
different parts of the actuating solenoid, a
second relay for controlling current flow to
said solenoid, a divided resistor, divisions of
said resistor connecting the second relay and
20 the actuating solenoid, said resistor so con-
nected as to provide a shunt path for the
initial operating current for the last men-
tioned relay, and provide a second ground re-
turn for the said relay after a predetermined
25 time due to the operation of the said relay to
increase its operating current.

14. In a system of the class described, the
combination of an actuating solenoid, a relay
operable to selectively direct currents thru
30 the different parts of the actuating solenoid,
and a retarded pickup relay for controlling
current flow to the circuit of the said sole-
noid, and means to reduce the operating cur-
rent of the said relay for a predetermined
35 time.

15. A switch operating system, comprising
in combination, an electrically operated
track switch, circuit controlling means oper-
ated automatically from a car to control said
40 circuit for transmitting current from the
conductor to the track switch to operate it
in the desired direction, and electrically op-
erated means equipped with means for re-
tarding current flow in a circuit compris-
45 ing a divided resistor arranged in shunt with
the said operating means to reduce the oper-
ating current for a predetermined time dur-
ing which the said shunt circuit is interrupted
and the said operating means is rendered in-
50 operative.

16. In a system of the class described, the
combination of a normally open circuit in-
cluding an actuating solenoid, a relay adapt-
55 ed to selectively direct currents thru differ-
ent parts of said solenoid, and a second relay
in circuit between the first mentioned relay
and the solenoid for controlling a flow of
60 saturating current thru either branch of the
solenoid, a divided resistor in circuit with
each solenoid branch and the said second re-
lay, a portion of the said resistor so arranged
as to be initially shunted about the operating
65 coil of the said second relay for a predeter-
mined time, wherein the said shunt is re-

moved and a second ground applied thru an-
other solenoid branch.

17. In a system of the class described, the
combination of a normally open operating
70 circuit including an actuating solenoid, a re-
lay adapted to selectively direct currents thru
different parts of said solenoid, a circuit
including a second relay having an armature
included in the said circuit and its operating
75 means included in a circuit connecting the
different parts of the solenoid thru a divided
high resistance, said resistance arranged and
connected to provide a shunt path for the said
operating means, means to close the said nor-
80 mally open circuit and establish a saturating
current through one branch of the actuating
solenoid and establish a current less than a
saturating value thru the other branch of the
solenoid and the divided resistor to effect the
85 operating means of the last mentioned relay.

In testimony whereof I affix my signature.
